UNITED STATES PATENT OFFICE.

HERMAN G. SCHILLER, OF LAWRENCE, MASSACHUSETTS.

SIGNAL LAMP AND MIRROR.

Application filed August 17, 1922. Serial No. 582,464.

To all whom it may concern:

Be it known that I, HERMAN G. SCHILLER, a citizen of the United States, residing at Lawrence, in the county of Essex and State 5 of Massachusetts, have invented certain new and useful Improvements in Signal Lamps and Mirrors, of which the following is a full, clear, and exact description.

My invention relates to lamps of the type 10 adapted to be attached to automobiles for the purpose of indicating to other drivers, pedestrians or traffic officers the intention of the operator to stop his machine or to alter its course.

15 An object of the invention is to provide an improved lamp casing of substantially oval shape and adapted to be opened at both the front and rear for the purpose of cleaning, changing the bulbs and the like.

20 Another object of the invention is the provision of a lamp adapted to be attached to the left front mud guard and which is provided with a convex mirror for the purpose of disclosing to the operator the condition 25 of traffic immediately in the rear.

Other objects and advantages of the invention will be apparent from the following description when taken in connection 30 with the accompanying drawing, in which,

Figure 1 is a rear view of the lamp.

Figure 2 is a front elevation of the lamp; and,

Figure 3 is a horizontal section on an enlarged scale.

35 Referring to the drawing more in detail, the numeral 1 designates the lamp casing which is elliptical in shape, and which is provided with a base 2 for attachment to the mud guard of an automobile. The casing 1 is formed with the integral rear wall 3 and the transverse partitions 4 which divide the casing into three compartments for housing the electric bulbs 5 which illuminate the signs.

40 Secured to the front of the casing 1 is the plate or lens 6 of glass or similar transparent material on which is indicated the words "Ahead", "Right" and "Left". This indicia may be placed directly on the plate 45 or a stenciled opaque plate may be placed over the plate 6 if desired. The invention

of course is not limited to any particular number of compartments, or to any particular indicia on the front of the lamp, as both may be varied according to requirements.

The plate or lens 6 is held in place by means of the ring 7 provided with the rolled edge 8, the ring being detachably connected to the main body of the casing by means of 55 the screws 9. A gasket or other packing material 10 may be positioned within the rolled edge 8 for excluding moisture, dust and the like.

Attached to the rear end of the casing 1 by means of screws 11 is the cover 12. This cover is provided with a rolled edge 13 which may receive a packing 14. The inner wall of the cover adjacent the rolled edge 13 is provided with two or more spring 60 clips 15 which are directed inwardly and rearwardly toward the rolled edge. These clips 15 have for their purpose to hold in place against the rolled edge 13 the convex mirror 16 and the lid or backing 17. The 65 cover 12 being removed from the lamp casing, it is only necessary to depress the springs 15 in order to remove the lid 17 and mirror 16 from their seat. In replacing the mirror and lid 17 the same are merely 70 forced past the clips 15 which automatically 75 spring back into place behind the lid.

From the foregoing description it will be seen that I have provided a neat and simple arrangement of lamp and mirror which is 80 composed of few parts and which may be readily assembled or disassembled as may be required.

What I claim as new and desire to secure 85 by Letters Patent is:

A combined lamp and mirror, including a casing having a circular rear wall and a cylindrical side wall, a lens secured at the open end of said casing, a substantially cylindrical cover detachably connected to said casing, a rolled edge formed on said cover, a mirror mounted in the cover and engaging the rolled edge, and spring fingers secured to the inner wall of the cover and forcing the mirror against the rolled edge.

HERMAN G. SCHILLER.
